UNITED STATES PATENT OFFICE.

JAMES H. REED, OF SWAMPSCOTT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SHOE-SEWING MACHINE.

Application filed November 11, 1922. Serial No. 600,224.

This invention relates to work clamping, feeding and incising mechanism for sewing machines and especially, although not exclusively, to lock-stitch shoe sewing machines of the general type shown in my prior applications for Letters Patent, Serial No. 439,225, filed January 22, 1921; Serial No. 491,897, filed August 13, 1921; and Serial No. 542,666, filed March 10, 1922; of which applications 5 this case is in the nature of a division in part and with respect to the subject matter which it has in common therewith.

The invention has for its object to provide an improved work-feeding awl or feed 15 point and operating mechanism therefor adapted to impart thereto a positive four-motion feed, said mechanism operating said awl to incise the work to a definite depth from the upper surface thereof and being, to 20 this end, operatively connected with and controlled by the presser foot or other movable work-clamping member, but nevertheless permitting the awl or feed point to remain in engagement with the work to feed the 25 same when the presser foot is raised to release the work; said awl or work-incising member being also of such a character as to form in the surface of the work a stitch-receiving channel, and to incise the work in 30 such a manner as to avoid weakening the same to an objectionable extent along the line of the seam.

The foregoing and other objects of the invention, together with means whereby the 35 same may be carried into effect, will best be understood from the following description of a preferred embodiment thereof illustrated in the accompanying drawings. It will be understood, however, that the particular construction described and shown has 40 been chosen for illustrative purposes merely, and that the invention, as defined by the claims hereunto appended, may be otherwise practised without departure from its spirit 45 and scope.

In said drawings:—

Fig. 1 is a side elevation of the head of the machine.

Fig. 2 is an enlarged front elevation thereof, showing also the upper end of the work-supporting horn.

Fig. 3 is a vertical section taken substantially on the line 3—3 of Figure 2.

Fig. 4 is a horizontal section taken substantially on the line 4 of Figure 2. 55

Fig. 5 is a fragmentary view of the mechanism for moving the feed point laterally to feed the work.

Fig. 6 is a similar view of the mechanism for moving the feed point toward and from 60 the work.

Fig. 7 is an enlarged plan view of the work, illustrating the operation of the combined awl, feed point, and channel former.

Fig. 8 is an enlarged front elevation, and 65 Fig. 9 an enlarged side elevation, of said combined awl, feed point and channel former.

Fig. 10 is a detail plan view of the presser foot. 70

The invention is herein illustrated as embodied in a machine of the type described in my prior applications above referred to. Said machine is adapted primarily for sewing McKay shoes, but is also capable of use 75 for many other purposes, as, for example, for stitching along the shanks on the inside of shoes of the Goodyear welt type. The machine sews a lock-stitch seam and has a straight, flattened, hooked needle 15 (see Figure 2) and a shuttle 16 supplying a shuttle 80 thread on the outer side of the sole of the shoe or other work W, while within the shoe, or at the opposite side of said work, there is a cooperating work-supporting horn 17 having in its tip an oscillating looper or whirl 85 18 supplying a cop or needle thread.

The needle 15 is carried by a needle bar 19 which is connected by a link 20 with a lever 21 pivoted in the head frame 22 and 90 operated by a cam 23 on the main shaft 24 journalled in said head frame 22 and adapted to receive power from any suitable source through a loose pulley 25 and a suitable clutch and stop mechanism 26. 95

The shuttle 16 is of the discoidal type and is mounted in a shuttle race 27 supported at the bottom of the head frame 22 in a position to hold the shuttle with its front face slightly inclined to the path of the needle. 100 The shuttle has a hook 28 projecting from its front face and extending circumferentially thereof, the arrangement being such that, as the shuttle is oscillated, said hook will cross the path of the needle, take the loop therefrom, and cast the same over the shuttle, said 105

hook passing at one side of the path of the needle when in its uppermost position. The shuttle 16 is oscillated by a shaft 29 (see Figure 1) having a pinion 30 (see also Figure 2) engaged by a rack 31 carried by an arm 32 pivoted in the head frame and operated by a cam 33 on the shaft 24.

The whirl 18 is oscillated, by mechanism not shown herein, to place a loop of cop thread in the open hook of the needle 15 when the latter is in its lowermost position, said loop being taken from the needle, when the latter rises, by the shuttle 16, and the shuttle thread being passed therethrough, as above explained.

The parts thus far referred to, except as they enter into combination with the parts hereinafter described, specifically form no portion of the present invention and may be 20 of any suitable construction and arrangement. They will, therefore, not be further discussed herein, as they are fully shown and described in my prior applications above referred to, and the foregoing explanation of 25 their nature and function will be sufficient for a complete understanding of the invention about to be described.

The work W is, during the stitch-forming operations, clamped upon the work-supporting horn 17 by a presser foot 34 carried by a presser foot bar 35 guided for vertical movement in the head frame 22. Said presser foot is pressed toward the work by a torsion spring 36 carried by a rod 37 supported at its ends 30 in brackets 38 and 39 secured to the top of the head frame 22, said spring engaging at one end a stud 40 carried by the presser foot bar 35. The presser foot 34, as shown in Figures 4 and 10, is preferably so shaped as 35 partly to surround the feed point 42, hereinafter referred to, and the path of the needle 15, and therefore to engage the work about the stitch-forming point. In order to permit the work to be fed, the presser foot is periodically lifted by mechanism comprising a slide 43 on the presser foot bar 35, said slide carrying a pivoted dog 44 which is engaged by a bell crank lever 45 pivoted to the head frame 22 and having a roller which cooperates with 40 a cam surface on the cam 23. The arrangement is such that, when the dog 44 is raised by the lever 45, it will first turn upon its pivot to engage the presser foot bar 35, the slide 43 being then lifted by the lever 45, acting 45 through the dog 44, and carrying with it the presser foot bar. As the dog 44 is released by the lever 45, it will, in turn, release the presser foot bar 35, permitting the spring 36 to depress the latter, the slide 43 being independently depressed by a spring 46 to an extent determined by the engagement of an adjusting screw 47 carried by said slide with an adjacent portion of the head frame 22. The stroke of the lever 45 being constant, it 50 will be seen that the movement imparted to

the slide 43 will depend upon the adjustment of the screw 47, being, however, constant in amount for each adjustment of said screw. The slide 43 and dog 44 constitute an intermittent grip device which cooperates with 70 the presser foot bar 35 to lift the latter a predetermined amount, irrespective of the initial position of said bar, this amount being equal to the amount of movement of said slide 43. It will, therefore, be seen that, irrespective 75 of the thickness of the work W, the presser foot 34 will at each operation of the machine be lifted the same distance above the upper surface of the work, this amount being determined by adjustment of the screw 47. 80

The presser foot may be lifted by the operator in order to permit the insertion or removal of the work by means of a lever 48 fulcrumed upon the bracket 39 and engaging at its forward end an opening in the presser 85 foot bar 35, said lever being operated through suitable connections by a treadle (not shown) at the base of the machine.

The presser-foot mechanism just described is not claimed herein, as it forms the subject 90 matter of a divisional application filed October 20, 1923, Serial No. 669,829.

Mounted for adjustment in suitable ways on the under side of the presser foot 34 is a sole edge guide 49, as shown in Figures 2, 95 3 and 10, said edge guide being secured in adjusted position by means of a screw 50.

The feed point 42 is suitably secured, as by a set screw 51, to the lower end of a feed foot 52. As shown in Figures 8 and 9, said feed point is formed with a cutting edge 53 arranged transverse, and preferably oblique, to the line of feed, and above said cutting edge 53 with a shoulder forming a cutting or indenting edge 54 disposed longitudinally or 100 in the direction of the line of feed. The cutting edge 53, which extends beyond the shoulder 54, is arranged to incise the work for the passage of the flattened needle, and thereby perform the function of an awl, the incisions, 105 which are shown at 55 in Figure 7, being transverse or oblique to the length of the seam, so as to avoid to as great an extent as possible weakening of the material between the needle holes. The edge 54, which is of a 110 length at least equal to that of the longest stitch, is adapted, upon successive operations of the feed point, to form a substantially continuous channel 56 in the face of the work to receive the seam 57. The edge 54 may be a 115 cutting edge to cut the stock, or may be relatively blunt so as to merely to indent the same, thereby, in effect, forming a continuous line of connected incisions constituting the channel 56.

The feed foot 52 is secured to or forms part of a feed point carrier slide 58 guided for movement toward and from the work in a feed slide 59 which, in turn, is guided for lateral movement on the head frame 22, or pref- 130

erably in a bracket 60 secured thereto and depending therefrom. The feed slide 59 is provided in its rear face adjacent one end with a vertical groove 61 which receives a block 62 pivoted to a slide 63 which is longitudinally adjustable on an arm 64, being held in adjusted position thereon by set screws 65. The arm 64 is carried by a sleeve 66 loosely mounted on a shaft 67 journalled in suitable bearings in the head frame 22. The sleeve 66 is formed with a pair of lugs 68 carrying abutment screws 69 which engage at opposite sides a lug 70 on a second sleeve 71 loosely mounted on the shaft 67. The sleeve 71 is formed with an arm 72 carrying a roller which cooperates with a cam 73 on the shaft 24. It will thus be seen that oscillation of the sleeve 71 will be transmitted through the lugs 70 and 68 to the sleeve 66 which, in turn, operating through the bar 64 and slide 63, will produce a positive lateral movement of the feed slide 59 and feed point 42 to feed the work when said feed point is in engagement therewith. The amount of such lateral feed movement, and consequently the length of the stitches, will be determined by the adjustment of the slide 63 on the arm 64, which determines the amplitude of movement of said slide. The point of engagement of the feed point with the work, irrespective of the length of the feed stroke, may be varied by adjustment of the abutment screws 69 to vary slightly the relative angular positions of the sleeves 66 and 71 upon the shaft 67.

35 The feed point carrier slide 58 is moved in the feed slide 59 to cause the feed point 42 to engage and incise or penetrate the work, and to disengage the same, by means of a bell crank lever 74 which is pivoted at 75 to the presser foot bar 35. One arm of the bell crank lever 74 has pivoted thereto a block 76 which is received in a transverse groove 77 in the slide 58, while the opposite arm of said lever is connected by a link 78 with a pin 80 projecting from an operating slide 79 guided for lateral movement in ways formed in the front face of the presser foot bar. It will be seen that lateral movement of the slide 79, as transmitted through the bell crank 74, will result in a vertical movement of the feed point carrier slide 58. The vertical position into which the feed point is moved by the bell crank lever 74 is not affected by the lateral movement of said feed point, since at this time the block 76 moves idly in the groove 77 which is parallel to the face of the work. The slide 79 is formed in its rear face adjacent one end with a vertical groove 81 in which is guided a block 82 pivoted to an arm 83 having a hub 85 suitably secured, as by a set screw 84, to the shaft 67. Also secured to said shaft, as by a set screw 86 (Figure 1), is a second hub 87 having a pair of spaced lugs 88 and 89. The lugs 88 and 89 receive between them a third lug 90 on a sleeve 91 loosely mounted on the shaft 67 and having an arm 92 provided with a cam roller cooperating with the cam 93 on the shaft 24. The lug 88 carries an abutment screw 94, while the lug 89 carries a hollow abutment screw 70 or threaded sleeve 95. By suitable adjustment of the abutment screws 94 and 95 the relative angular position of the hubs 87 and 91 may be determined, thereby determining the limits of movement of the feed point 75 with respect to the presser foot. The adjustment of these abutment screws will always be such as to provide a certain amount of lost motion between said screws and the lug 90 which is normally held against the abutment screw 94 by a plunger 97 guided in the sleeve 95 and backed by a spring 96 whose tension may be adjusted by a screw 98 in threaded engagement with the interior of said sleeve. As will now be seen, movement of the sleeve 85 91 and lug 90 in a clockwise direction will be followed by a corresponding clockwise movement of the lugs 88 and 89, sleeve 87, shaft 67, and arm 83, and a consequent movement of the feed point 42 toward the work until 90 said feed point encounters a resistance sufficient to cause the spring 96 to be compressed, whereupon the lug 90 will engage the abutment screw 95, and the remaining portion of the movement of the feed point to penetrate 95 the work will be a positive one. Inasmuch, however, as the lever 74 is carried by the presser foot bar 35, and, therefore, movable with the presser foot, the lifting of the latter would tend to disengage the feed point 100 from the work. When the presser foot rises, however, the spring 96 again expands, causing the feed point to remain in its depressed position. Upon movement of the lug 90 in a counter-clockwise direction, engagement 105 thereof with the abutment screw 94 will cause a positive movement of the arm 83 in a counter-clockwise direction and a positive withdrawal of the feed point from the work.

110 It will thus be seen that the mechanism above described provides a four-motion feed in which all of the movements are positively effected. It will also be seen, however, that, notwithstanding the positive actuation of the feed point, the latter is permitted to remain 115 in engagement with the work when the presser foot is lifted, although the mechanism for moving the feed point toward and from the work is carried, in part, by the presser foot and controlled by the position 120 thereof. The latter provision is an important one, inasmuch as it causes the work-penetrating movements of the feed point to be controlled by the position of the presser foot and consequently by the thickness of 125 the work. The movement of the feed point may be varied somewhat by adjustment of the abutment screws 94 and 95, this adjustment being a manually effected one in accordance with the requirements of any particular 130

class of work, but the limits of this movement of the feed point, and particularly the starting point thereof, will also be automatically varied in accordance with the thickness 5 of the work, thereby causing the feed point to penetrate the work a constant amount and form a channel 56 of constant depth irrespective of the thickness of the work.

Having thus described my invention, I 10 claim:

1. In a shoe sewing machine, stitch-forming instrumentalities including a needle, an awl located on the same side of the work as the needle for incising the work for the 15 passage of said needle, said awl having an edge disposed transverse to the length of the seam produced by said stitch-forming instrumentalities, and means for actuating the awl to form an incision extending only partially 20 through the work.

2. In a shoe sewing machine, the combination with stitch-forming mechanism including a hook needle, of feeding mechanism including a work engaging and feeding member 25 on the same side of the work as the needle having edges disposed respectively in the direction of and transverse to the line of feed and adapted respectively to form in the work a substantially continuous channel to receive the seam and a series of transverse incisions for the passage of the needle.

3. In a sewing machine, the combination with stitch-forming instrumentalities, of a 35 presser foot, and work feeding mechanism comprising a feed slide guided for lateral movement in a direction parallel to the surface of the work, means for reciprocating said slide, and a feed point movable on said slide in a direction toward and from the work, said 40 feeding mechanism being connected with said presser foot to vary the operative position of said feed point with different thicknesses of work.

4. In a sewing machine, a presser foot and 45 work feeding mechanism comprising a feed slide guided for lateral movement in a direction parallel to the surface of the work, a member movable on said slide towards and from the work and provided with a feed 50 point, and devices for positively operating said slide and member respectively, one of said parts being connected with said presser foot to vary the operative position of said feed point with different thicknesses of work.

5. In a sewing machine, a movable presser 55 foot, a feed slide, an arm for operating said slide, a feed point movably mounted on said slide, a lever pivoted to said presser foot for operating said feed point, and means including an arm and a link for operating said lever.

6. In a sewing machine, a vertically movable presser foot, means for lifting said presser foot, a feed point operatively connected with said presser foot and movable

therewith toward and from the work and also movable laterally to feed said work, and means for actuating said feed point, said actuating means being adapted to cause said feed point to engage the work when said 70 presser foot is lifted.

7. In a sewing machine, a movable presser foot, a feed slide, an arm for operating said slide, means for connecting said arm and slide, a feed point carried by said slide and 75 movable thereon toward and from the work, a lever pivoted to said presser foot and operatively connected with said feed point, an arm for operating said lever, and means for operating said arm, said parts including a 80 yielding connection adapted to hold said feed point in engagement with the work when said presser foot is raised.

8. In a shoe sewing machine, in combination, a feed point, a work engaging member 85 controlled as to its position by the thickness of the work, means controlled by said work engaging member for moving said feed point with relation to said member toward and from the work to engage and release the same, and additional means for moving said feed point laterally to feed the work when in engagement therewith.

9. In a shoe sewing machine, in combination, a presser foot, a feeding member, means 95 independent of said presser foot for supporting and guiding said member, and means connected with said presser foot for moving said member toward and from the work and varying its position with different thicknesses of 100 work.

10. In a shoe sewing machine, in combination, a presser foot, a feed point, means independent of said presser foot for supporting said feed point and for guiding the same for 105 lateral movement to feed the work, and means carried by said presser foot for moving said feed point towards and from the work.

11. In a shoe sewing machine, in combination, a presser foot, a feed point, means independent of said presser foot for supporting said feed point and for guiding the same for lateral movement to feed the work, means carried by said presser foot for imparting to said feed point a stroke of constant length 115 toward and from the work, and means for reciprocating said feed point laterally.

12. In a shoe sewing machine, in combination, a frame, a presser foot, a member mounted on said frame for lateral feeding movement, means for operating said member, a feed point movable on said member to engage and disengage the work, and means carried by said presser foot for actuating said feed point.

13. In a shoe sewing machine, in combination, a frame, a presser foot, a feed slide guided on said frame for lateral movement, means for reciprocating said slide, a feed point movable on said slide to engage and 130

- disengage the work, and means carried by said presser foot for actuating said feed point.
14. In a shoe sewing machine, the combination with a presser foot, of feeding mechanism including a laterally movable member, means for operating the same, a feed point movable on said member to engage and disengage the work, a lever fulcrumed on said presser foot for actuating said feed point, 10 and means for operating said lever.
15. In a shoe sewing machine, the combination with a frame and a presser foot mounted thereon for movement toward and from the work, of feeding mechanism including a feed 15 slide guided for lateral movement on said frame, means for reciprocating said slide, a feed point slide guided on said feed slide for movement toward and from the work, a feed point carried by said feed point slide, a lever 20 fulcrumed on said presser foot and operatively connected with said feed point slide, and means for operating said lever.
16. In a shoe sewing machine, the combination with a presser foot, of feeding mechanism including a feed point movable toward and from the work and laterally to feed the same, and means for actuating said feed point including a bell crank lever pivoted to said presser foot, a grooved slide guided by said 25 presser foot and operatively connected with said lever, and an operating member engaging the groove in said slide.
17. In a shoe sewing machine, the combination with a frame and a presser foot carried 30 thereby, of feeding mechanism including a member mounted for lateral feeding movement on said frame, means for operating said member, a feed point movable on said member to engage and disengage the work, and means for actuating said feed point including a bell crank lever pivoted to said presser foot, a grooved slide guided by said presser foot and operatively connected with said lever, and an operating member engaging the 35 groove in said slide.
18. In a shoe sewing machine, in combination, a presser foot, means for lifting the same, a feeding member, means independent of said presser foot for supporting and guiding said member, and mechanism, including a part carried by said presser foot, for positively actuating said feeding member, said mechanism having provision for permitting said presser foot to be lifted without moving 40 said member.
19. In a shoe sewing machine, in combination, a feed point, means for reciprocating said feed point laterally to feed the work, a presser foot, means for lifting the same, and mechanism, including a part carried by the 45 presser foot, for positively forcing said feed point toward the work and for positively withdrawing the same therefrom, said mechanism including a resilient lost motion connection to cause said feed point to remain in en-
- gagement with the work when said presser foot is lifted.
20. In a shoe sewing machine, in combination, a feed point, means for reciprocating said feed point laterally to feed the work, a 70 presser foot, means for lifting the same, means carried by said presser foot for moving said feed point toward and from the work, an operating member for said last named means, an actuator having a lost motion connection with said operating member for positively moving said member in both directions, and a spring interposed between said actuator and operating member.
21. In a shoe sewing machine, in combination, a work engaging member, a work incising member, and actuating means for moving said work incising member with relation to said work engaging member towards and from the work connected with and controlled by said work engaging member to cause said work incising member to penetrate the work to a constant depth irrespective of the thickness of the latter.
22. In a shoe sewing machine, the combination with stitch-forming mechanism, of feeding mechanism including a work engaging and feeding member having an edge disposed in the direction of the line of feed and adapted to form in the work a substantially continuous channel to receive the seam, and means for moving said member with its edge toward and from the work, said machine having provision for causing said member to penetrate the work to a constant depth irrespective of the thickness of the latter.
23. In a shoe sewing machine, a work incising member, means for imparting to said member a stroke toward and from the work of constant length, and means controlled by the thickness of the work to vary the limits of said stroke and thereby cause said member to penetrate the work to a constant depth irrespective of the thickness of the latter.
24. In a shoe sewing machine, a work incising and feeding member, means for imparting to said member a work feeding movement, means for imparting to said member a stroke toward and from the work of constant length, and means controlled by the thickness of the work to vary the limits of said stroke and thereby cause said member to penetrate the work to a constant depth irrespective of the thickness of the latter.
25. In a shoe sewing machine, feeding mechanism including a feed point, a slide by which said feed point is carried, said slide having a transverse groove, a lever having means to engage said groove, means for operating said lever to move said feed point and slide toward and from the work, and means for moving said feed point and slide laterally to feed the work.
26. In a shoe sewing machine, the combination with a presser foot, of feeding

mechanism including a feed point, a slide by which said feed point is carried, said slide having a transverse groove, a lever pivoted to said presser foot and having means to engage said groove, means for operating said lever to move said slide and feed point toward and from the work, and means for moving said slide and feed point laterally with respect to said presser foot to feed the work.

27. In a shoe sewing machine, stitch-forming mechanism including a straight hook needle, a work supporting horn arranged to extend within the shoe, needle threading mechanism located in the horn, work feeding mechanism and means for forming in the tread surface of the shoe sole during the sewing operation a stitch receiving channel of constant depth irrespective of the thickness of the work.

28. In a shoe sewing machine, stitch-forming mechanism including a straight hook needle, a work supporting horn arranged to extend within the shoe, needle threading mechanism located in the horn, a feeding member having a channel forming portion disposed in the direction of the line of feed, and means for actuating said member to feed the work and form in the tread surface of the sole a stitch receiving channel of constant depth irrespective of the thickness of the sole.

29. In a shoe sewing machine, the combination with a frame and a presser foot carried

thereby, of feeding mechanism including a member mounted on said frame for lateral feeding movement, means for operating said member, a feed point movable on said member to engage and disengage the work, and means controlled by the presser foot for actuating the feed point to engage and disengage the work.

30. In a shoe sewing machine, stitch-forming mechanism including a straight hook needle, a work supporting horn arranged to extend within the shoe, needle threading mechanism located in the horn, work feeding mechanism including a work feeding member having an edge disposed in the direction of the line of feed and adapted to form in the work a substantially continuous channel to receive the seam, and means for actuating said member positively to penetrate the work to a constant depth irrespective of the thickness of the latter.

31. In a shoe sewing machine, stitch-forming mechanism including a straight hook needle, a work supporting horn arranged to extend within the shoe, needle threading mechanism located in the horn, a presser foot, a feed point, means independent of the presser foot for supporting and guiding the feed point for lateral movement to feed the work, and means controlled by the presser foot for moving the feed point towards and from the work.

In testimony whereof I affix my signature.
JAMES H. REED.
